United States Patent

Des. 241,121

Patented Aug. 24, 1976

241,121

COMBINED JAR AND CLOSURE

Floyd E. Pettengill, Lancaster, Ohio, assignor to General Foods Corporation, White Plains, N.Y.

Filed Apr. 14, 1975, Ser. No. 567,463

Term of patent 14 years

Int. Cl. D9—01

U.S. Cl. D9—157

FIG. 1.

FIG. 2.

FIG. 3.

FIG. 4.

FIG. 1 is a top perspective view of a combined jar and closure showing my new design;

FIG. 2 is an elevational view thereof;

FIG. 3 is a top plan view thereof; and

FIG. 4 is a bottom plan view thereof.

I claim:

The ornamental design for a combined jar and closure, as shown and described.
